UNDERFLOOR WIRING DUCT UNIT

James W. Hudson, Lexington, Ky., assignor to Square D Company, Park Ridge, Ill., a corporation of Michigan

Filed May 14, 1963, Ser. No. 74,882

Term of patent 14 years

(Cl. D26—5)

FIG. 1 is a top plan view of an underfloor wiring duct unit, showing my new design;

FIG. 2 is a side elevational view, the opposite side being substantially a mirror image thereof;

FIG. 3 is a perspective view; and

FIG. 4 is an end elevational view, the opposite end being substantially a mirror image thereof.

The bottom of the duct is essentially flat and plain.

Portions of the duct unit are broken away in the drawing figures for convenience in illustration.

I claim:

The ornamental design for an underfloor wiring duct unit, as shown and described.
